DESIGN FOR A SLED KNEE

Carl W. Sundberg, Birmingham, Mich., assignor
to Pratt Manufacturing Company, Coldwater,
Mich., a copartnership

Application June 27, 1946, Serial No. 131,069

Term of patent 14 years

(Cl. D34—15)

To all whom it may concern:

Be it known that I, Carl W. Sundberg, a citizen of the United States, residing at Birmingham, Oakland County, Michigan, have invented a new, original, and ornamental Design for a Sled Knee, of which the following is a specification, reference being had to the accompanying drawing, forming a part thereof, in which:

Fig. 1 is a top plan view of a sled knee, embodying the design of the present invention;

Fig. 2 is a side elevation; and

Fig. 3 is a rear elevation of the sled knee shown in Fig. 1.

The broken line showing of portions of a conventional sled construction are for illustration purposes only.

I claim:

The ornamental design for a sled knee, as shown and described.

CARL W. SUNDBERG.
